UNITED STATES PATENT OFFICE.

GRANT McELHANY, OF WATERTOWN, SOUTH DAKOTA.

BUCKET.

SPECIFICATION forming part of Letters Patent No. 737,449, dated August 25, 1903.

Application filed March 18, 1903. Serial No. 148,382. (No model.)

To all whom it may concern:

Be it known that I, GRANT McELHANY, a citizen of the United States, residing at Watertown, in the county of Codington and State 5 of South Dakota, have made certain new and useful Improvements in Buckets, of which the following is a specification.

My invention is an improvement in buckets, and especially in buckets designed for use in 10 elevating grain and the like; and the invention consists in certain novel constructions and combinations of parts, as will be herein-after described and claimed.

In the drawings, Figure 1 is a perspective view of a bucket embodying my invention. 15 Fig. 2 is a detail perspective view of the harness or brace frame of the bucket. Fig. 3 is a vertical section of the bucket. Fig. 4 is a bottom plan view of the bucket, and Fig. 5 is 20 a detail perspective view of the door.

My bucket is especially designed for use in elevating grain where it is desired to raise grain for filling bins from an upper floor. It becomes desirable in such connection to provide 25 a bucket of large capacity which will be of sufficient strength to sustain the weight and stand hard usage and which will be provided with a dumping-door arranged to be released by a tripping-rope, so its contents can 30 be discharged by the operator standing at a distance. The bucket, as shown, comprises the main or outer casing A, the inner or funnel-shape casing B, and the bracing-frame, together with the dumping bottom or door C. 35 The casing A is cylindrical in form and extends below the funnel B, so it will protect the latter at all times.

The bracing-frame D is best shown in Fig. 2, and consists of the upper and 40 lower rings D' and D'', the intermediate ring D³, the upright rods D⁴ and D⁵, the downwardly-converging rods D⁶, and the door-ring D⁷, secured to and between the inner lower ends of the downwardly-converging bars D⁶.

At their upper ends the bars D⁶ are secured 45 to the inner side of the central ring D³ at points opposite their respective upright bars D⁴ or D⁵, the whole constituting a strong bracing-frame for both the casing and the 50 funnel, as will be understood from Figs. 1 to 4 of the drawings.

The casing A fits within the rings D', D'',

and D³ and is suitably riveted thereto. The upper ends of the bars D⁶ project at d⁶ above the funnel B and within the casing A, as best 55 shown in Fig. 3, the funnel B being fitted within the cone-shaped basket formed by the bars D⁶ and being riveted at its upper end at b to the casing A, adjacent to the ring D³, and at its lower end to the door-ring D⁷, within which 60 the cylindrical nipple B' at the lower end of the funnel B fits, as best shown in Fig. 3 of the drawings. The bars D⁴ project at d⁴ above the top ring D' and afford connection for the bail E, as shown in Figs. 1 and 2. 65

The door C is hinged at C' at the lower end of the funnel B and is provided with a spring-actuated sliding bolt C² for engagement with a depending lug F at the side of the ring D⁷, opposite the hinge C', the swinging edge of the 70 door C being notched at C³ to fit the lug F and the plate or wing C⁴, formed by notching the door C, being turned down to afford a guide for the bolt C², as shown in Fig. 5 of the drawings. The bolt C has connected with it the 75 rope G, which leads from the bolt through the casing A to convenient reach of the operator, so he can pull upon the rope or cord G to release the bolt and permit the door to open and the contents of the bucket to discharge. The 80 rope G has a knot G' to prevent the rope from pulling on the door after the bolt has been released.

By the described construction it will be seen I provide a bucket which will be strong and 85 serviceable, as the casing is reinforced by the bars D⁴ and D⁵, and the upper, lower, and intermediate rings and the funnel-shape bottom is supported and reinforced by the frame therefor, consisting of the downwardly-converging 90 bars D⁶, supported from the bracing-frame of the casing and carrying at their lower ends the door-ring, which reinforces the discharge-orifice of the funnel-shape bottom and furnishes a strong support for the door and its 95 latching devices.

In practice it is designed to make the buckets to hold from ten to twenty bushels and to rig them on a hoist, one horse being ordinarily able to handle about ten bushels and two 100 horses twenty bushels. The bucket may be placed on the ground and filled with the grain and then drawn by the team to the proper height and carried along to the dumping-point,

and the operator by drawing on the check-rope can open the door in the bottom of the bucket, letting the grain discharge.

Having thus described my invention, what 5 I claim, and desire to secure by Letters Patent, is—

1. The improvement in buckets herein described, comprising the bracing or harness-frame consisting of the upper, lower and intermediate rings, the upright bars extending outside of and secured to said rings, the downwardly-converging bars secured at their upper ends to and within the intermediate ring, the door-ring secured to the lower inner ends 10 of the converging bars, the casing secured within the upper, lower and intermediate rings, the funnel-shape bottom supported by the converging bars and secured at its upper end within the casing and at its lower end 15 20 within the door-ring, the door for closing the lower discharge end of the funnel, the spring-actuated bolt for securing the door in its closed position, and the rope by which to release the said bolt, substantially as and for 25 the purposes set forth.

2. A bucket substantially as described, comprising the outer casing, a bracing-frame therefor, an inner bracing-frame within the casing and diverging downwardly, the funnel-shape bottom supported by said converging 30

frame, and the door for closing the discharge of said bottom substantially as set forth.

3. A bucket comprising the casing, the harness or bracing frame fitting around and secured to the casing and extending to the lower 35 edge thereof and the funnel-shape bottom within the casing and terminating at its lower end above the lower end of the casing substantially as set forth.

4. The combination of the casing, the bracing-frame fitting around and secured to same, the funnel-shape bottom within the casing and the bracing-frame supporting said bottom and secured to the frame of the casing 40 substantially as set forth.

5. The combination of the upper, lower and intermediate rings, the bars D⁴ and D⁵ extending between and secured to said rings, the bars D⁴ being projected above the upper ring to afford connection for the bail, the bail, 45 the downwardly-converging bars D⁶ secured at their upper ends to the intermediate ring, the door-ring carried by the lower ends of the bars D⁶, the casing, the funnel-shape bottom, and the door all substantially as and 50 for the purposes set forth.

GRANT McELHANY.
